UNITED STATES PATENT OFFICE.

JACOB SCHAUB, OF NEWARK, NEW JERSEY, ASSIGNOR TO THE THEROZ COMPANY, OF NEW YORK, N. Y., A CORPORATION OF DELAWARE.

FILLING-MACHINE.

1,397,184.

Specification of Letters Patent.

Patented Nov. 15, 1921.

Application filed July 5, 1918. Serial No. 243,267.

To all whom it may concern:

Be it known that I, JACOB SCHAUB, a citizen of the United States, and residing in Newark, county of Essex, and State of New Jersey, have invented certain new and useful Improvements in Filling-Machines, of which the following is a specification.

This invention relates to improvements in machines for filling receptacles, especially cans, with fluid or semi-fluid materials temporarily liquefied solid materials, particularly what is known as solidified alcohol, fats, oils of various kinds, especially edible vegetable oils, syrups, molasses, paraffin and cold creams and the like, and has for its objects the provision of a simple, efficient and durable mechanism adapted to supply a predetermined quantity of such materials to the receptacles to be filled.

Heretofore, various machines have been constructed for supplying such fluid or semi-fluid material to containers to be filled therewith, but either the mechanism thereof was such as not to lend itself to convenient adjustment so as to instantly vary the quantity of material being supplied, or else the machines were complicated and expensive and easily deranged, or the machine was found to be ill-adapted for supplying accurately regulated quantities of heavy viscous materials to the receptacles therefor at regulated intervals.

My invention is fully set forth and described in the accompanying specification and drawings forming a part thereof, in which—

Figure 1 is an elevation of one side of a machine embodying my invention;

Figs. 1^a and 1^b are detailed plan views, with the shafts in section, along the lines 1^a, 1^a and 1^b, 1^b, respectively of Fig. 1;

Fig. 2 is an elevation of the reverse side of said machine;

Fig. 3 is a plan view showing the position of the parts of the machine when in a filling position;

Fig. 4 is a partial plan view with the caps closed showing the cans being moved into the filling position;

Fig. 5 is a fragmentary vertical section through the conveyer belt with the cans thereon shown in elevation;

Fig. 6 is a partial vertical section along the lines 6—6 of Fig. 3;

Fig. 7 is a detail elevation along the line 7 of Fig. 6;

Fig. 8 is a sectional view of the friction clutch taken along the line 8—8 of Fig. 2; and

Fig. 9 is a plan view partially in section taken along the line 9—9 of Fig. 6.

Referring to the drawings and the construction shown therein, the reference numeral 1 designates the longitudinal member of the supporting frame of the machine, the same being suspended from suitable straps (not shown) and being connected by bolts 2. Longitudinal guides 3, 3' and 4, 4' which preferably consist of angle irons are secured together by bars 5 to form a so-called magazine for the cans A which it is desired to fill.

The said guide members 4, 4' are split at one end and their upper faces a are curved upwardly so as to admit of the ready reception of cans beneath said faces when it is desired to insert the same into said magazine. The same upper faces of said guides are cut partially away at the opposite ends b to permit of the ready removal of said cans when filled. A cut-off or delivery receptacle, herein termed a bisected ladle or cuvette, is formed by two hinged members 6, 6' respectively, that are mounted on shafts 7 and 7' carried by a bracket 8 rigidly supported from the longitudinal member 1 of said frame. The members 6, 6' are respectively provided with meshing gears 9 and 9' slidably fitted on shafts 7, 7', for removal, the gear 9 being keyed or otherwise secured to shaft 7. The shaft 7 is provided at its outer end with a segmental gear 10 which is rigidly secured thereto and adapted to be rotated to and fro as hereinafter described, whereby said ladle members will be alternately forced into an open and shut position, as shown in Figs. 1 and 9 respectively.

A belt conveyer 11 passes over rollers 12 and 13, the upper surface thereof being substantially in alinement with the upper horizontal faces c and c' of the lower guides 3, 3' and as a consequence when said belt is driven, as hereinafter described, any cans placed upon the faces c, c' of said guides will be carried along by said belt until the same are delivered to an operator waiting to receive the same. An elbow-rack 14 which coacts with said segmental gear 10 intermittently actuates the ladle members in unison with the movement of a star feed-wheel 15 actuated by means of a special form of Geneva movement.

The elements of said Geneva movement consist of two parallel shafts 16 and 17 suitably mounted in the bracket 18, the former having a bevel gear 19 at its upper 5 end which is adapted to mesh with a companion gear 20 on the shaft 21, journaled in said bracket 18, and carrying the positively driven roller or spool 12.

The said shaft 16 is provided with a spool 10 member 22 which is adapted to receive between its flanges a serrated wheel 23, having six recesses 24, mounted on the shaft 17. A roller 25 is mounted between said flanges of the spool 22 and the same is adapted, 15 when the shaft 16 is being rotated, to enter successively into each of the said six recesses thereby positively driving the wheel 23 through one-sixth revolution. In order to frictionally hold the shaft 17 against 20 accidental movement, except when the wheel 23 is being rotated by the roller 25, I form an annular hub 26 on the end of the lower end of the spool 22 and secure a star wheel 27, having a sleeve 27', on the end of the 25 shaft 17. The hub 26 is provided with a marginal recess 28, positioned immediately below the roller 25, which is of such a configuration as to admit of the successive reception of the respective points of the star 30 wheel 27 during the rotation of the shafts 16 and 17. Accordingly, the periphery of the hub 26 will normally project between the two adjacent points of the star wheel 27 except during the brief interval when 35 one of the points of said star is projecting into the recess 28, with the result that when the star wheel 27 is in the position shown in Fig. 1^b it will remain stationary and there will be no possibility of the star feed wheel 40 15, which will be in the position shown in Figs. 1 and 6, being accidentally moved so as to displace a can from its filling position until the ladle members are in a substantially closed position. The shaft 21 is provided at its other end with a gear 29 which 45 is splined thereto and a cam or hub-member 30 is secured to said gear. The cam is shown having an annular portion and provided with a recess 31 having an inclined 50 steep face 32 and an inclined face 32' into which a roller 33, carried by the long arm 14' of the elbow rack 14, is adapted to periodically enter and leave when the gear-wheel 29 revolves counter clockwise in Fig. 55 1. Cam 30 is shown adjustably secured to gear 29 by means of a screw 29^a passing through a slot in gear 29 and threaded in cam 30, (Figs. 2 and 6,) whereby the cam may be adjusted and retained in set position 60 on gear 29 for timing the operation of the member 14.

The longer arm 14' of said elbow rack 14 is pivotally connected to a bar 14'' which latter is in turn pivotally secured to the

frame of the machine. A weight *d* is swung 65 from said arm 14', and serves to cause said roller 33 to periodically drop into the recess 31 as it rides along the periphery of the hub 30.

The gear 29, carrying with it the disk or 70 hub-member 30, is adapted to be actuated by a gear 34 rigidly secured on a shaft 35 which is journaled in the said frame. The outer end of said shaft 35 is provided with a gear 36 that is actuated by a worm 37 on 75 the longitudinally extending shaft 38 which is connected by a knuckle 39 and intermediate shaft 40 and knuckle 41 to the shaft 42. A worm 43 on the shaft 42 engages a gear 44 on the shaft 45 carrying the roller 13. 80 An electric motor B is adapted to drive a shaft 46 journaled in the frame of the machine, and the latter shaft, through an intermediate friction clutch mechanism, drives said shaft 38. 85

Said clutch mechanism consists of a friction drive-wheel 47 which is keyed on the shaft 46 so as to be longitudinally adjustable thereon and is adapted to frictionally engage and effect the rotation of a disk 90 member 48 rigidly mounted on the end of the shaft 38.

In order to effect the accurate and convenient regulation of the speed of the shaft 38, I provide a spindle 49 which is mounted 95 in the frame of the machine and carries a worm 50 by which the optional rotation of the shaft 38 is effected through the agency of a rack 51 slidably mounted in guides 52 and connected by a fork 53 to said drive 100 wheel 47. Said guides 52 carry a stationary bearing 54 which receives shaft 46.

The regulation of the speed of the main shaft 38 is readily and instantly effected by merely rotating the hand wheel of the spindle 49 either in a clockwise direction to increase the speed of an anti-clockwise direction to decrease the speed and thereby the friction drive-wheel 47 is moved radially across the face of the disk wheel 48 with a result that the speed imparted to the said disk will vary in accordance with the radial position of the drive wheel 47 along the face of the disk wheel 48. 110

In order that the ladle members may be 115 readily removed for cleaning or for other reasons, I provide a spring-catch 56 which is secured at one end to the bracket 8 and has an inturned end 57 that is adapted to normally project into the annular grooves 120 58, 58' on the gears or pinions 9, 9'. A bar 59 of semi-circular cross-section projects beneath said spring 56 and is adapted to normally lie in the position shown in Fig. 6 but when turned through a one-half revolution by means of a handle 60 it will raise the spring 56 to a sufficient extent to release the pinions 9, 9' carried by the members 6, 6'

and thereby permit of the removal of said ladle members by pulling them off shafts 7, 7'.

The operation of the machine, as is apparent from the foregoing description, is as follows:—

The shafts 38 and 40 are rotated by the motor through the friction-clutch mechanism, the latter being adjusted to the speed desired and the rotation of said shafts being in such a direction as to effect the rotation of the gear 29 and its cam-member 30 counter clockwise in Fig. 7. Thereupon the shafts 21 and 45, which carry the belt-conveyer rollers 12 and 13 respectively, will be rotated in the direction of the arrow shown in Fig. 2. The shaft 16 which is geared to the shaft 21, will be revolved continuously, while the shaft 38 continues to rotate and at each revolution of said shaft 16 the roller 25 will advance the disk 23 through one sixth of a revolution thus causing the star feed wheel 15 to also advance one sixth of a revolution. Consequently, if a can is in engagement with one curvilinear face of said feed-wheel, such for example as shown in Figs. 3 and 6, it will be advanced toward the right hand side in Fig. 3 a distance equal substantially to the diameter of the can. Practically simultaneously with the movement of a can out of the filling position, the roller 33 will enter the recess 31 and this will cause the arm 14 of the elbow rack to drop and effect the rotation of the segmental pinion 10 sufficiently to move the shafts 7 and 7' into the position shown in Fig. 9, thus closing the cuvette temporarily while the next can is being moved into the filling position by the star feed-wheel. The function of the belt-conveyer, which travels continuously as long as the shaft 38 rotates is to move each can forward until in contact with the can immediately in front of it, in order that the star feed-wheel 15 which holds each can, while being filled in a stationary position, can embrace the can immediately following the filled can as the latter is moved out of a filling position by the said belt.

The elapsed time between the opening and closing of the ladle as well as that during which the can being filled is held stationary, can be instantly adjusted by the mere manipulation of the hand-wheel on the spindle 49. As a consequence, after having adjusted the feed of the material to the can being filled, it becomes unnecessary to automatically weigh each can when filled as is often customary in those cases where it is essential to have a minimum quantity of material packed in a container, as a mere occasional weighing of a can enables the operator to determine the exact quantity of material delivered into the can. As a consequence

not only is it possible to dispense with expensive and complicated automatic weighing machines, but owing to the simplicity of my machine and its ease of adjustment and operation, a single operator is able to attend several machines and this obviously effects a not inconsiderable saving in the cost of manufacture.

The foregoing machine has been found to be especially effective for filling cans with what is known as solidified alcohol while the same is in a fluent state as the necessity for the employment of small delivery pipes which would on each stoppage of the machine become almost instantly clogged by the rapidly solidifying of the material is entirely avoided and accordingly such material can be expeditiously packed in cans as conveniently almost as if it were a non-viscous liquid.

In Fig. 1 I have shown the cups 6, 6' spaced below a delivery nozzle X located over the receptacle can or to be filled, which nozzle may be in communication with any suitable supply for the liquid or material in a fluent state to be charged into the receptacles or cans. Such material flows continuously through said nozzle toward the cans below and the alternate closing and spreading apart of the cups will be such that when a can is about charged the cups 95 will close to cut off the supply to the can without stopping the flow of the material from the nozzle, and the cups will remain closed until the succeeding empty can is placed beneath the cups whereupon they 100 will spread to admit a charge into said can, and so on for successive cans. During the time that the cut-off cups are closed they will trap and temporarily accumulate a portion of the charge for the succeeding 105 can so that when the cups next open or spread such part charge will be delivered into the cans to be followed by a further flow of material through the cups to be cut off when such can is filled, and so on. In other 110 words, the construction disclosed is such that charges of desired size may be filled in the cans periodically in accordance with the time of successive operations of closing and opening the cups, whereby while the cups 115 are open the material may continue to flow into the cans for the desired charge therein, the closing of the cups cutting off the material for each charge, the cups receiving and accumulating a portion of the next charge 120 while the filled can is being removed and an empty can is placed under the cups, whereby the flow of the material for the cans may be continuous. The machine is particularly adapted for charging containers with predetermined quantities of fluent yet viscous material, such as set forth in my Letters Patent No. 1,262,267, granted April 8, 1918.

Having thus described my invention, what I claim and desire to secure by Letters Patent is:—

1. In a machine for filling receptacles, the combination consisting of a bisected ladle having two substantially similar members mounted on separate parallel shafts, said shafts being provided with gears meshing with each other, a segmental gear secured 10 to one of said shafts, a reciprocating rack co-acting with said segmental gear, means for effecting the to and fro movement of said rack at predetermined intervals whereby the alternate opening and closing of said ladle is 15 effected, a feed mechanism including a star wheel, the latter being adapted to partially embrace a receptacle between two adjacent arms thereof, means including a Geneva movement for periodically moving and stopping said wheel in synchronism with the closing and opening of said ladle, a conveyor for supplying receptacles into a position to be periodically embraced by said star wheel during the movement of the latter and 20 means, including a friction drive mechanism for effecting the synchronous movement of said ladle members and said feed mechanism.
2. In a filling machine, the combination 25 of a delivery nozzle for fluent material, a cut-off spaced below said nozzle in the path

of material therefrom, said cut-off comprising complemental cup-like members pivotally supported on parallel shafts having meshing gears adapted to cause said members to close to cut off and accumulate said material without stopping its flow from the nozzle, and to separate to deposit said accumulated material and permit the flow of additional material through the cut-off, and 35 means to periodically actuate said gears to open and close said members.

3. In a filling machine, the combination of a delivery nozzle for fluent material, a cut-off spaced below said nozzle in the path 40 of material therefrom, said cut-off comprising complemental cup-like members having opposing edges to meet adapted to close to cut off and accumulate said material without stopping its flow from the nozzle, and to 45 separate to deposit said accumulated material and permit the flow of additional material through the cut-off, parallel shafts rotatively supporting said members in spaced relation, gearing connecting said shafts for 50 rocking them in opposite directions, and means to periodically operate said gearing to cause said members to open and close.

Signed at New York in the county of New York and State of New York, this 2nd day of July, 1918.

JACOB SCHaub.
